ROBERT T. POWERS Inventor

By Richard Oliver, Attorney

UNITED STATES PATENT OFFICE.

ROBERT T. POWERS, OF NORTH OXFORD, MASSACHUSETTS.

LUG-STRAP SUPPORT.

1,418,396.

Specification of Letters Patent. Patented June 6, 1922.

Application filed December 31, 1921. Serial No. 526,346.

To all whom it may concern:

Be it known that I, ROBERT T. POWERS, a citizen of the United States, residing at North Oxford, in the county of Worcester 5 and State of Massachusetts, have invented certain new and useful Improvements in a Lug-Strap Support, of which the following is a specification.

The present invention relates to lug strap 10 supports or an attachment to a picker stick of a loom used in textile weaving machinery.

The principal object of the invention is to provide a device of this nature which is extremely simple and efficient in construction, 15 well adapted to the purpose for which it is designed, reliable in operation, and capable of being manufactured at a comparatively low cost.

Another object of the invention is to provide 20 means for attaching the lug strap to the picker stick without the necessity of driving nails or screws therein which tend to split the stick and greatly interfere with its strength and efficient operation.

Another object of the invention is to provide 25 a lug strap support of this nature which is capable of being readily adjustable so as to accommodate various needs in this art, said adjustment being capable of being made 30 with considerable ease and speed.

With the above and numerous other objects in view, the invention resides in certain novel features of construction, and the combination and arrangement of parts as will 35 be hereinafter more fully described and claimed.

In the drawing:—

Figure 1 is an elevation of the lug strap support showing the same in conjunction 40 with a picker stick and lug strap,

Figure 2 is a vertical central section taken therethrough,

Figure 3 is a transverse section taken on the line 3—3 of Figure 1,

Figure 4 is an end elevation of the parts shown in Figure 1, and

Figure 5 is a detailed perspective of the screw plate.

Referring to the drawing in detail it will 50 be seen that 1 designates a picker stick which may be of any conventional construction as is now commonly used with looms in the textile trade. A supporting bar 2 is positioned adjacent one edge of the picker 55 stick 1 and is formed with angularly ex-

tending lips 3 and 4 at its end. A U-shaped collar 5 is disposed about the picker stick 1 and has its terminals situated adjacent the lower end of the supporting bar 2. The legs of this collar 5 are provided with the 60 ledges 6 upon which is adapted to rest the lug strap 7 which is connected to the sweep stick 8 by the bolt 9. Registering slots 10 are provided at the terminals of the legs of the collar 5 for receiving a screw receiving 65 plate 11 which is notched at 12 adjacent its terminal for engagement with the edges of the slots 10 as is seen to advantage in Figure 3. A central internally threaded bore 13 extends transversely through the plate 11 70 so as to receive a screw 14 which is adapted to abut the support bar 2 as is seen in Figure 3 so as to hold it in frictional and firm engagement with the picker stick 1.

By the construction just described it will 75 be readily understood that all the danger of splitting the picker stick by placing screws or nails therein is eliminated and further, that the various parts of the attachment may be easily adjusted so as to be moved 80 in relation to the picker stick up or down for the power that may be desired and further that the collar will greatly prolong the life of the picker stick since the same acts as a binder thereabout and also forms a firm 85 support for the lug strap, preventing it from riding down upon the picker stick 1 while the lip 3 prevents it from riding up thereon. The lip 4 of the supporting bar 2 prevents the collar 5 from moving downwardly in 90 relation to the picker stick since it would engage the screw receiving plate 11 as is seen to advantage in Figure 2.

The modification which I have just described and shown in the accompanying 95 drawings represents the preferred example of my invention but it is, of course, to be understood that numerous changes in form, and in the proportion, combination and arrangement of parts may be resorted to without departing from the spirit of the invention as hereinafter claimed.

Having thus described my invention what I claim as new is:—

1. In combination, a picker stick, a lug 105 strap therefor, a supporting bar including an angularly extending lip at each end, a U-shaped collar on said stick and receiving said supporting bar adjacent its lower terminal between its ends, the ends of said 110

collar being provided with registering slots, a plate situated in said slots, and screw threaded through said plate for engagement with said supporting bar so that the same 5 may be forced thereagainst so as to press the bar in frictional engagement with the picker stick.

2. In combination, a picker stick, a lug strap therefor, a supporting bar including 10 angularly extending lips at its terminals, a U-shaped collar situated on the picker stick so as to receive the lower end of said bar between its terminals, said terminals being

provided with registering slots, a bar provided with a pair of notches projecting 15 through said slots so as to engage their edges in its notches, and a screw threaded through said plate for forcing the bar in frictional engagement with the picker stick.

In testimony whereof I affix my signature 20 in presence of two witnesses.

ROBERT T. POWERS.
